GAS BURNER

Herbert J. Long, Springfield, and Hans Albrecht, West Springfield, Mass., assignors to American Bosch Corporation, Springfield, Mass., a corporation of New York

Application November 2, 1937, Serial No. 172,364

1 Claim. (Cl. 158—115)

This invention relates to gas burners and more particularly to gas burners of the type having a thermostatically controlled pilot associated therewith.

5 It is a primary object of our invention to provide a compact arrangement of the main and pilot burners in which the pilot is in close proximity to each of the jets of the main burner.

The invention further resides in certain details 10 of structure and arrangement of parts which facilitate the manufacture and assembly of the burner and therefore materially reduce the cost thereof.

15 The above and other objects and features of the invention will be apparent to those skilled in the art from a consideration of the following detailed description taken in conjunction with the accompanying drawings, in which:

Fig. 1 is a top plan view; Fig. 2 is a section on the line 2-2 of Fig. 1; and Fig. 3 is a plan view partly in section of a burner casting.

Referring to the drawings, reference numeral 1 indicates an annular casting forming a gas manifold 2. The casting is provided with an outwardly projecting portion 3 providing an inlet passage 4 adapted for connection to a gas mixing tube 5. The casting 1 forms an almost complete circle which terminates in a dead end portion adjacent to but spaced from the inlet 4 of the gas manifold 2. Spaced passages 6 extend upwardly through the casting providing communication between the gas manifold 2 and a plurality of upwardly extending burner tubes 7. These burner tubes are supported upon shouldered portions 8 of the passages 6 and are flattened at their upper ends to terminate in fish tail type gas jets 9. This construction provides a plurality of long, narrow gas jets which extend substantially radially of the annular casting 1.

40 The casting 1 is provided with a plurality of inwardly projecting lugs 10 which are adapted to support a tubular member 11 centrally of the annular casting. The tubular member is provided with outwardly projecting lugs 12 adapted for attachment to the lugs 10 by means of screw bolts 13 inserted through suitable openings in the lugs. The tubular member 11 has a reduced portion at its lower end forming a gas inlet passage 14, and an enlarged portion at its upper end 45 which is internally screw-threaded to accommodate a safety pilot control device 15. The safety control device consists of a screw plug 16, the lower end of which provides a seat 17 for a safety valve 18. The valve 18 is provided with a stem 19 which projects upwardly through the plug 16

and is attached to a disc thermostat 20. The thermostat 20 is supported in a sheet metal housing 21, the lower end of which is brazed or otherwise permanently fixed to the interior of the upper portion of the screw plug 16, and the upper end of which supports a pilot burner 22. The screw plug 16 is provided with lateral passages 23, intermediate the ends thereof, which provide communication between the central portion of the screw plug and an angular passage 24. An outwardly projecting annular boss 25 on the enlarged portion of the screw plug 16 is internally screw-threaded to accommodate a discharge tube 26 leading from the annular passage 21. The passage 26 lies above the annular casting 1, the space between two of the passages 6 being somewhat greater at this point to permit the discharge tube 26 to pass between two of the burner tubes 7. A torch supply tube 27 opens into the gas inlet passage 14 below the valve 18 and extends outwardly through the break in the annular casting 1 formed by the space between the inlet end and the dead end thereof. The tube 27 is provided with an enlarged end portion to accommodate a torch valve 28 which is controlled by a push button 29 which projects outwardly beyond the circumference of the casting 1.

A control cock 31 is provided in the discharge passage 26 and a tube 32 leads from the control cock 31 to a thermostatic control valve 33 which may be responsive to the temperature at any desired point as, for example, to the temperature of the water where the burner is used in connection with a hot water heater. From the control valve 33 the gas passes by way of a tube 34 to the inlet end of the mixing tube 5. 30 35

A cylindrical casing 35 having an internal diameter corresponding to the external diameter of the annular casting 1 is attached at its lower end by means of fastening screws 36 to the casting 1. Bayonet slots or equivalent fastening means are provided at the upper end of the casing 35 for convenient attachment to a heater casing or other structure with which the burner is to be used. The casing 35 and the attached casting 1 therefore provide a complete burner cup to which secondary air is supplied through the annular passage 38 provided between the tubular member 37 and the casting 1. Additional secondary air is supplied through lateral openings 39 in the cylinder 35. 40 45 50

The pilot burner 22 is of the general type shown and claimed in our copending application Serial No. 108,126, filed October 29, 1936, and need not be here described in detail except to point 55

out that it provides a low continuous annular flame slightly above the open upper ends of the burner tubes 7 and in close proximity to each of them. A screw valve 40 of sufficient length to 5 extend outwardly to or through an opening in the casing 35 is provided for adjacent the pilot flame. In the operation of the device it will be understood that when starting from cold the safety valve 15 is closed so that no gas is supplied to 10 either the main or the pilot burner. The pilot burner is ignited by manually holding the torch valve open by means of the push button 29 and igniting the gas which issues from the torch tube 30 toward the pilot burner 22. The torch flame 15 heats the pilot burner housing until the disc thermostat 20 opens the valve 18 and gas is thus supplied to the pilot burner. Gas also thereupon passes through the lateral openings 23 and thence through the discharge passage 26 to the thermo- 20 static control valve 33. If the medium to be heated is cold this valve will be in open position and gas will be supplied through the passage 34 to the mixing tube 5 and thence through the gas manifold to each of the burner tubes 7. Thus 25 the flow of gas will continue until the medium heated reaches the desired temperature at which

time the thermostatic valve 33 will close cutting off the flow of gas to the main burners while the flow of gas to the pilot continues.

While there is herein described but a single embodiment of the invention other embodiments 5 within the scope of the appended claim will be obvious to those skilled in the art.

Having thus described the invention, what is claimed is:

A gas burner comprising a hollow casting of 10 substantially circular form providing a manifold, a tubular casing detachably secured to the periphery of said casting, said casting and tube forming a burner cup substantially closed at its lower end except for a central opening, a gas supply 15 tube extending through said opening and supported by said casting, a pilot-controlled safety valve mounted upon said supply tube, a pilot burner mounted above said safety valve, burner tubes extending from said manifold and having 20 jets adjacent said pilot burner, and passaged means extending from a point between said valve and said pilot burner for conducting gas from said supply tube to said manifold.
